UNITED STATES PATENT OFFICE.

JAMES R. MAHAFFY, OF WILMINGTON, DELAWARE.

VETERINARY DENTAL FLOAT.

SPECIFICATION forming part of Letters Patent No. 741,519, dated October 13, 1903.

Application filed May 29, 1903. Serial No. 159,289. (No model.)

To all whom it may concern:

Be it known that I, JAMES R. MAHAFFY, residing at Wilmington, in the county of Newcastle and State of Delaware, have invented 5 a new and Improved Veterinary Dental Float, of which the following is a specification.

My invention seeks to provide an improved construction of veterinary dental float or tool of that character including a handle or supporting means, file or cutter devices mounted thereon for smoothing and leveling the teeth of horses, and means co-operatively joined with the support or handle portion for actuating said cutter or leveling devices, and my 10 invention in its generic nature comprehends a simple and economical construction of dental appliance of the character stated in which the file of leveling-member-actuating means is especially adapted for connection with an ordinary foot - power driving mechanism, which includes a flexible shaft, whereby the tool *per se* can be conveniently held by one or both hands and the same operated by foot-power.

25 In its more complete nature my invention embodies a tubular handle or supporting body, a file or cutter member reciprocably mounted on one end thereof, a rotating member adapted to be coupled to and actuated by a flexible drive-shaft, a means co-operatively joined with said rotating member for transferring a reciprocal motion to the file or cutter; and in its more subordinate features my invention consists in certain details of construction and peculiar combinations of parts, all of which will hereinafter be fully described, and specifically pointed out in the appended claims, reference being had to the accompanying drawings, in which—

40 Figure 1 is a perspective view of my improved dental tool. Fig. 2 is a longitudinal section of the same, the parts being especially arranged for operating on the front teeth of a horse. Fig. 3 is a cross-section taken on the line 3 3 of Fig. 4. Fig. 4 is a plan view of the form of file or cutter device shown in Fig. 2. Fig. 5 is a longitudinal section of a modified form of my dental implement especially adapted for filing or cutting the molar 45 or back teeth of a horse. Fig. 6 is an enlarged section of the rotary cam and the casing

therefor shown in Fig. 5. Fig. 7 is a plan view of the file or cutter devices shown in Fig. 5, and Fig. 8 is a cross-section of the same on the line 8 8 of Fig. 5.

55 In the practical application of my invention I provide a supporting body or handle, which is a tubular shaft 1, exteriorly threaded at both ends. At the front end of said shaft is mounted a file or cutter holding frame, which 60 in the form of my invention illustrated in Figs. 1 to 4 consists of a flat body 2, having a longitudinal socket or channel-way 2^a in the upper face, the side walls of which are formed with dovetailed grooves 2^x 2^x to receive the 65 dovetailed sides 3^x 3^x of the file or cutter member 3 in the nature of a flat blade having teeth or serrations on the opposite faces, preferably of different texture, whereby the 70 said member when reversibly adjusted will present a fine or coarse cutting or filing surface, as the condition of the teeth to be treated may make desirable, and to provide for readily reversing the said member 3 the inner end of the channel-way 2^a is open to permit the 75 said end member being slid endwise therein, as will be clearly understood by reference to Fig. 2, from which it will also be noticed the member 3 is so positioned with respect to the bottom of the channel-way 2^a that the teeth 80 at the lower side are in a plane above the bottom to hold them from rasping or scraping thereon during the reciprocable motion of the cutter or file.

85 At the inner end the frame 2 has an integral pendent portion 2^c, the inner end of which is in the form of a hub c, centrally apertured, as at c', and formed with a threaded socket to fit on the outer end of the tubular handle 1, and the outer end of the portion 2^c 90 forms a circular socket 2^d, with which the aperture c' communicates.

Within the socket 2^d is rotatably held a cylindrical block 4, provided with an S-shaped cam-groove 4^a in its peripheral face to receive 95 the shank 5^a of a screw-stud 5, mounted on the inner end of the member 3.

6 designates a cylindrical stem rotatably mounted within the tubular handle 1, the outer end of which extends through the aperture c' and is fixedly connected to the cam 4, and the inner end 6^a of said stem extends be-

yond the inner end of the handle 1 into the socket-piece 7, provided with a hub 7^a, having a threaded aperture whereby to fit on the inner end of the said tubular handle 1, as 5 clearly shown in Fig. 2, and the said inner end 6^a of the stem has a collar 8, provided with an eye 8^a to receive the loop end 9^a of the flexible drive-shaft 9, which in the practical arrangement of my invention connects 10 with and is driven from a foot-power lathe in any well-known manner.

The cutter-piece 7 at one end of the tubular handle 1 and the cam member 4 at the other end thereof serve to hold the stem 6 15 from unnecessary longitudinal play.

So far as described the manner in which my dental implement operates is best explained as follows: The operator grasps the tubular portion with one or both hands and holds the 20 same steady with the file or cutter end over the front tooth or teeth to be treated, it being understood that when power is applied in any well-known manner to rotate the flexible drive-shaft 9 the continuous rotary motion imparted to the stem 6 within the handle will through the medium of the cam member 4 reciprocate the file or cutter member 3 on its holding-frame.

By reason of the peculiar correlative arrangement of the file or cutter, its holding-frame, and the actuating means shown in Figs. 1 and 2 it is difficult to conveniently use the said arrangement of my invention for trimming the back molar teeth, and to provide 35 for properly treating the said back molar teeth as conveniently as it is possible to treat the front teeth with the form of my implement shown in Figs. 1 to 4 I employ a slightly-modified arrangement of my invention, which 40 is illustrated in Figs. 5, 6, 7, and 8. In this latter form the file or cutter member 3 is disposed in the plane of the longitudinal axis of the handle or body 1, and the said member 3 is also slidably supported in the frame 20, 45 which terminates at the inner end in an apertured hub 20^a, adapted to screw onto the outer end of the member 1, and the outer end of the stem 6 slides in the aperture of the hub 20^a and has a threaded nipple 6^c, that engages 50 a threaded socket in the inner end of the cutter or file member 3, as clearly shown in Fig. 5. In the said modified form the inner end of the body 1 carries a hollow socket-piece 10, having a threaded hub for engaging 55 the threaded end of the member 1, and within the said socket is held the rotary cam 11, having the S-shaped groove 11^a, with which connects a stud-pin 12, fixedly held on the socket-piece 10, and the cam 11 has a 60 threaded socket 11^b to receive the threaded end 13^a of the eyepiece 13, with which the flexible drive-shaft 9 connects, and the said socket 11^b also receives a headed end 6^d of the stem 6, on which the cam member 12 freely 65 rotates and which by reason of its cam-slot moves longitudinally within the socket 10,

and thereby reciprocably actuates the stem 6 within the tubular handle and imparts the desired reciprocation to the file or cutter member 3.

Since my improved implement can be held in and manipulated with one or both hands of the operator, who drives the same by foot-power, it is manifest that no unnecessary bearing or steadyng of the implement within the horse's mouth is required, and as the operator has both hands free he can conveniently adjust the tool with respect to the teeth being treated and without loosening, wrenching, splintering, or otherwise injuring the 75 teeth.

Having thus described my invention, what I claim, and desire to secure by Letters Patent, is—

1. A veterinary tool of the character described, comprising a handle, a file-holder detachably secured to one end thereof, said holder having guide-flanges, a file or cutter member mounted in said holder in engagement with said guide-flanges and reciprocably slidably therein, means for imparting reciprocable motion to the file or cutter member mounted in the file-holder, said means including a flexible rotary drive-shaft and connections co-operatively joining the said drive-shaft with the file or cutter member mounted within the holder for transmitting a reciprocable motion to the said cutter or file from the rotary drive-shaft, for the purposes specified.

2. A veterinary tool of the character described, comprising a hollow handle, a file-holder having a hollow hub detachably connected to one end of said handle, said file-holder having guide-flanges, a file mounted within said file-holder having its edges in engagement with said guide-flanges and adapted for reciprocable movement within said holder, a drive-shaft mounted within and inclosed by said hollow handle, a cam member mounted upon one end of the drive-shaft within the hollow hub of the file-holder, said cam member having a cam-groove, a stud detachably connected to said file and projected into the said cam-groove, a hollow hub connected to the other end of said hollow holder, a check-nut secured to said drive-shaft within said last-named hollow hub, said check-nut having an eye portion adapted to receive a flexible drive-shaft, for the purposes specified.

3. In a veterinary implement of the character stated, a handle, a longitudinally-extended guideway on the front end thereof, a cutter or file member reciprocably slidably and reversibly mounted in the said guideway, a rotary stem mounted on the handle and connections, including rotary cam devices co-operatively joined with the file or cutter member for imparting reciprocable motion thereto as the stem is rotated, for the purposes described.

4. In a veterinary implement of the character stated, the combination with a supporting member including a hollow tubular handle, and entirely inclosed thereby, a stem rotatable within the said handle, a guide extended longitudinally from the front end of the handle, a cutter or file member reciprocably slideable in the said guide, a cam mounted on the stem provided with a cam-slot, a stud on the file or cutter engaging said cam-slot, and means for imparting a rotary motion to the stem, substantially as shown and described.
5. An improved veterinary implement of the character described, comprising a tubular handle, a frame detachably secured to the front end thereof and extended lengthwise therefrom, said frame including an open-top guideway, and a centrally-apertured hub for engaging the forward end of the handle, a stem rotatable within the handle, a disk mounted on the forward end thereof having an S-shaped groove, a stud, a socketed hub mounted on the opposite ends of the tubular handle, a hub member mounted therein and attached to the outer end of the rotary stem, and a flexible rotary drive-shaft connected to the said hub, all being arranged substantially as shown and described.
6. In a veterinary implement of the character described, the supporting-handle, a rotary stem mounted in the said supporting-handle, a cam-disk carried by the said stem, an extension on the front end of the handle, said extension having an open-top guideway provided with guide-grooves in its opposite sides, a cutter or file blade having serrations on its opposite faces and its edges shaped to slide in the grooves of the guideway, said grooves in the guideway being disposed relatively in the bottom of the guideway whereby to sustain the file or cutter with its lower edge in a plane above the bottom of the guideway, and connections between the cam on the rotary stem and the file or cutter member, all being arranged substantially as shown and for the purposes described.
7. A veterinary tool of the character described, comprising a tubular handle, a file-holder detachably connected to one end thereof, said file-holder including a hub portion and a file-carrying portion, said file-carrying portion having guide-flanges, a file or cutter member mounted in said file-carrying portion with its edges in engagement with the guide-flanges and one of its file-faces exposed, means for imparting reciprocal motion to the file or cutter member, said means including a shaft passing through the tubular handle, a cam mounted within the file-holder hub and connected with the end of the shaft, a screw-stud

secured to the file and held in engagement with the cam and means for imparting a rotary motion to the shaft, for the purposes described.

8. An improved veterinary implement of the character described, comprising a tubular handle, said tubular handle being externally threaded at each end, a frame having a threaded portion adapted to be screwed on the end of said shaft and extended lengthwise therefrom, said frame including an open-top guideway and a centrally-apertured hub, said open-top guideway including guide-flanges, a stem rotatable within the handle, a cam member mounted on the forward end thereof having an S-shaped groove, a file adapted for reciprocal movement in said open-top guideway with its edges in engagement with the guide-flanges thereof, said file having a plurality of file-faces and being so arranged that but one file-face is exposed, said file having a threaded aperture, a stud having a threaded portion adapted to be secured into said threaded aperture and projected downward into the S-shaped groove of the cam, a hollow hub mounted on the opposite end of the tubular handle, a drive-shaft having a threaded portion at one end, and a connecting member on the said threaded portion within the hollow hub on the end of the handle opposite the detachable frame and a flexible rotary drive-shaft connected to the said connecting member for the purposes specified.

9. In a veterinary implement of the character described, a hollow handle 1 threaded at both ends, a hollow member 7 having a threaded portion 7^a, and adapted to be secured to the threaded end of the hollow handle 1, a file-carrier 2 including a hub portion 2^c having a screw-threaded portion adapted to screw onto the other end of the handle 1, said file-carrier including a rectangular guideway arranged parallel with the hollow handle and having guide-flanges 2^a, a file member mounted within said file-holder and having its sides in engagement with the guide-flanges, said file including an upper and lower file-surface, and a threaded aperture, a rotary drive-shaft 6 mounted within said hollow handle 1 and having a cam member 4 at one end, and a connecting member 8 at the other end, means for connecting the said file with said cam member and means for imparting a rotary motion to the drive-shaft to reciprocate the file, said file being arranged with but one file-face exposed for the purposes specified.
